UNITED STATES PATENT OFFICE.

GEORGE E. GOLDNER, OF FORT DODGE, IOWA.

APPARATUS FOR FINISHING THE ENDS OF HOLLOW CLAY ARTICLES PREPARATORY TO DRYING AND FIRING.

1,128,597.

Specification of Letters Patent. Patented Feb. 16, 1915.

Application filed February 12, 1913. Serial No. 743,020.

To all whom it may concern:

Be it known that I, GEORGE E. GOLDNER, a citizen of the United States, residing at Fort Dodge, in the county of Webster and State of Iowa, have invented certain new and useful Improvements in and Relating to Apparatus for Finishing the Ends of Hollow Clay Articles Preparatory to Drying and Firing, of which the following is a specification.

This invention relates to certain improvements in and relating to apparatus for finishing the ends of hollow clay articles preparatory to drying and firing; and the objects and nature of the invention will be readily understood by those skilled in the art in the light of the following explanation of the accompanying drawing illustrating what I now believe to be the preferred mechanical expression of my invention from among other formations, constructions and arrangements within the spirit and scope of my invention and that might be employed in carrying out my method.

An object of the invention is to provide an apparatus for and method of finishing the end edges of green hollow blocks, tiles or the like, that are left rough by the cutting off wires or other devices for severing the hollow clay bar into sections, while such hollow soft or green sections are in transit from the cutting off devices to the cars on which said sections are delivered to the drier preparatory to firing or burning.

A further object of the invention is to finish and simultaneously press mortar-key forming grooves in the end edges of green or soft clay hollow blocks, tiles or the like, after such blocks or tiles have been severed from the clay bar emerging from the die of a suitable machine and before said blocks or tiles have been dried preparatory to firing.

A further object of the invention is to provide an off-bearing belt adapted to receive green or soft clay hollow blocks or tiles from a cutting off device and convey the same to the cars or other means for delivering said blocks or tiles to a drier for drying preparatory to firing, with means for smoothing and finishing end edges of such blocks or tiles.

The invention consists in certain novel features in construction and in combinations and arrangements and in an improved

method capable of being practised by such apparatus among others.

Referring to the accompanying drawings:—Figure 1, diagrammatically illustrates an off-bearing conveyer equipped in accordance with my invention, a green tile being shown thereon with a portable hand-manipulated finishing cup or mold applied to the upper end thereof, several other green tiles being indicated on said conveyer by dotted lines. Fig. 2, is a detail plan view of the working face of either a hand-manipulated cup or one of the cups attached to the conveyer. Fig. 3, is a detail perspective of a hollow tile building block showing the end edge formation produced by said mold or cup. Fig. 4, is a detail cross section on the line 4—4, Fig. 2. Fig. 5, is a cross section with a cup or mold particularly designed to finish the ends of hollow clay pipe or drain tile sections. Fig. 6, is a detail section showing the ends of a pair of building blocks of the construction of Fig. 3, joined by a cement or mortar joint.

Hollow tiles, building blocks and the like, are usually formed by cutting the soft clay bar issuing from the die of a suitable machine into sections of the proper length by cutting apparatus usually embodying cutting wires. These soft or green sections are then placed or deposited on an off-bearing belt or conveyer that carries them to the point where the cars to convey said green sections to the drier are loaded. After drying said sections are fired or burned, as those versed in the art will understand. The off bearing belt or conveyer, usually consists of a comparatively wide flexible endless traveling belt having its top ply arranged flat and horizontally to receive the green sections from the cutting apparatus and support and carry them to a point from which the operators can easily remove said sections from the belt and place them on the drier or other cars. The end edges of the soft clay or green sections are left ragged, rough and uneven by the action of the cutting wires, and if the sections are left with their edges in this condition and are thus dried and fired, the resulting fired product will be unsightly, defective and unsatisfactory.

I have devised improved hollow building blocks and tiles having mortar receiving grooves sunk in their end edges so that

when such blocks are laid end to end and joined by cross joints formed by interposed bodies or layers of cement or mortar, said grooves in the end edges of adjoining blocks 5 or tiles will register and the mortar will enter the same and thus form keys locking said joints or layers of mortar against falling from the block or tile ends. In carrying out my invention, I propose to simultaneously 10 finish or dress the ends of the soft or green clay sections and press such grooves therein. This method can be carried out by providing properly shaped molds or cups to fit the opposite ends of each section and under the 15 necessary pressure to so compress and mold said ends as to smooth and flatten the same and sink the desired mortar receiving grooves therein.

A series of spaced similar molds or cups 20 can be arranged longitudinally of the off-bearing belt, each cup being bolted or otherwise secured thereto and arranged on the outer surface thereof. The operator will then place each soft clay section in an up- 25 right or vertical position on the receiving end of the belt, with the lower end of the section properly fitted and centered in one of said cups and upheld and supported thereby. The operator will be provided 30 with a similarly-shaped portable mold or cup having a handle or otherwise so formed that the operator can carry and manipulate the same. The operator will then properly center and fit this portable or hand cup on 35 the upper end of said section supported by and being carried forward by the belt, and will apply the necessary downward force or pressure thereto (longitudinally of the clay section) to mold and press both ends of said 40 section into said opposite cups and reduce said section ends to the desired shape and finish. When the ends of said section have been reduced to the shape and finish desired, the operator can remove the portable cup or 45 mold from the upper end of the section, and the section can be removed at the delivery end of the belt or other conveyer.

In the drawings, I show an endless off 50 bearing belt 1, carried by suitable horizontally arranged pulleys 2, one of which constitutes a drive pulley. The upper ply of this belt is preferably arranged flat and horizontal from its receiving end *a*, to its delivery end *b*. On the outer surface of 55 this belt I arrange a longitudinal series of spaced similar separate individually-complete cups or molds 3. Each cup is suitably bolted or otherwise secured to the belt so as to travel therewith and when at the top 60 of the belt to rest horizontally on and parallel with the top ply thereof with the operative side of the cup exposed at the top thereof to receive the lower end of a soft clay section, such as *c*. Each cup 3, can 65 consist of a flat block or suitable material

with its inner flat face resting against the outer face of the belt, and with its exposed outer or operative flat face formed (within the boundaries of such face) with a depressed open top matrix, groove or socket 4, 70 to vertically receive the end of the soft clay section and compress, dress or finish the end face and edge thereof to remove roughness and unevenness and produce smooth surfaces and straight or regular corners of the 75 desired sharpness or other formation. The side or vertical walls of said socket preferably diverge upwardly to center and guide the end of the clay section in seating itself in the mold or socket and to compress and 80 smooth out the corners or edges of the section end. The floor of the socket or mold is of the desired formation to reduce the end face of the clay section to the shape or form desired and smooth the surfaces thereof. 85 For instance, in the examples illustrated, the floor of the socket is formed with a central or intermediate longitudinal or continuous elevated rib 5, usually of an inverted V-shape in cross section. This rib will centrally and vertically enter the face of the section end and will thereby compress the clay laterally to and against the surfaces of the socket and will thereby aid in smoothing and finishing the section end and will 90 furthermore form the mortar receiving groove or locked cross joint 7, in the completed section end. The portable or hand operated cup or mold 8, that the operator applies to the upper end of the section has 95 a groove or socket and rib of the same shape and formation as the cups that receive the lower ends of the sections so that the upper ends of the sections will be dressed and finished the same as the lower ends thereof. 100 The portable or hand manipulated cup 8, can be of sufficient weight, if so desired, to produce the necessary clay section shaping or molding pressure or this pressure can be applied to the portable mold by the hand 105 of the operator. The cups will have the design of their sockets or grooves corresponding to the end view design of the tile or block, to be handled. The clay sections are 110 successively placed on the off bearing belt 115 so that said belt may be continuously carrying forward a number of said sections.

I show a mortar or cement joint 9, formed between the ends of a pair of hollow blocks of my invention with the mortar extending into and filling said grooves and thereby forming keys 10. The utility and advantage of this formation will be obvious to those skilled in the art. Of course however, all features of my invention are not limited 120 to the formation of such mortar receiving grooves and where the ends of hollow drain tiles are to be dressed, I may omit the ribs from the bottoms of the grooves or sockets 125 in the cups, as shown by the cup 3', (Fig. 5) 130

having the finishing groove 4', with a flat floor.

Other apparatus might be employed to carry out my improved method, and 5 changes, variations, and modifications might be resorted to in the forms, constructions and arrangements described without departing from the spirit and scope of my invention, and hence I do not wish to limit 10 myself to the exact disclosures hereof.

What I claim is:—

1. In an apparatus for finishing the ends of green hollow or tubular clay tiles and blocks, a traveling conveyer provided with 15 and carrying a series of tile or block supporting cups arranged longitudinally and externally thereof, and each provided with a tile or block end receiving and finishing socket, each cup adapted to carry a green tile or 20 block while being transported in a vertical position by the conveyer with its lower end fitted to the cup, in combination with molding means for applying variable manually-controlled molding pressure downwardly on 25 the upper end of each green tile or mold while traveling with said conveyer.

2. In an apparatus for finishing the ends of green hollow or tubular clay blocks and tiles, a traveling conveyer provided with a 30 longitudinal series of molds traveling therewith and each at its outer face formed to receive and shape an end of a green hollow article, and a portable or hand mold of approximately similar formation to receive 35 and shape the other end of such article.

3. Means for finishing the ends of green clay blocks and the like, comprising a traveling block-end-finishing cup formed to receive and finish the lower end of a vertical 40 tile or block being transported on said cup, in combination with manually-controlled finishing means for application to the upper end of said tile to finish the same while being transported in said vertical position.

4. In apparatus for the purposes substantially as described, in combination, means to transport green clay blocks and the like in a vertical position comprising a block-end-finishing cup in which the lower end of the 50 block fits and by which it is finished, and a manually-controlled block-end-finishing cup for application to the upper end of said vertical block to finish the same while being transported by said means.

5. In apparatus for the purposes substantially as described, an off-bearing conveyer

provided with green clay block end finishing cups, in combination with a hand-controlled block-end-finishing cup for application to the free end of a block having one end seated in a cup of the conveyer. 60

6. Apparatus for finishing and forming mortar receiving grooves in the end edges of green clay hollow blocks and tiles, comprising means for transporting said blocks 65 or tiles while maintaining the same in vertical position, said means embodying tile or block-end-finishing-and-groove-forming cups in which the lower ends of the blocks or tiles fit, and tile or block end finishing- 70 and-groove-forming means for applying variable manually controlled finishing and molding pressure downwardly on the upper end of each tile or block while being transported. 75

7. In apparatus for finishing the ends of green clay hollow or tubular blocks and tiles, means for transporting hollow green articles in vertical position embodying a mold formed to receive and shape the lower end 80 of a hollow green article, in combination with a hand applied mold of approximately similar formation to receive and shape the upper end of such article.

8. Traveling means adapted to receive 85 hollow green clay blocks and the like from cutting off mechanism and to transport said blocks in vertical position, said means embodying devices to receive and finish the lower ends of such blocks while resting 90 thereon and being transported thereby, in combination with manually controlled means for application to the upper ends of said blocks while being transported by said traveling means for finishing the upper ends 95 of the blocks.

9. A horizontally disposed off-bearing conveyer adapted to receive and transport hollow green clay blocks and the like in vertical position and formed to finish the 100 lower ends of blocks resting on the conveyer by the downward pressure of the blocks thereon, in combination with manually controlled means for finishing the upper ends of said blocks while said blocks are being transported by said conveyer. 105

In testimony whereof I affix my signature in presence of two witnesses.
